UNITED STATES PATENT OFFICE.

ROBERT W. LONG AND GEORGE BURESS, OF INDIANAPOLIS, INDIANA; SAID BURESS
ASSIGNOR TO SAID LONG.

STARTING DEVICE FOR INTERNAL-COMBUSTION ENGINES.

1,038,401.

Specification of Letters Patent. Patented Sept. 10, 1912.

Application filed August 10, 1911. Serial No. 643,461.

To all whom it may concern:

Be it known that we, ROBERT W. LONG and GEORGE BURESS, citizens of the United States, and residents of Indianapolis, county 5 of Marion, and State of Indiana, have invented a certain useful Starting Device for Internal-Combustion Engines; and we do hereby declare that the following is a full, clear, and exact description thereof, reference being had to the accompanying drawings.

The object of this invention is to provide an improved means for starting internal combustion engines and has particular application to the starting of automobile engines, whereby the driver will not be compelled to leave the seat in order to start the engine.

The particular feature lies in the manner 20 in which the fly wheel of the engine is gripped and rotated whereby it is not necessary that the engine remain on compression during the time it is stopped.

Another feature of the invention is the 25 means by which the parts are returned to their normal and idle position.

The nature of the invention will be understood from the accompanying drawings and the following description and claims.

In the drawings, Figure 1 is a plan view 30 of the forward portion of an automobile chassis with parts broken away and parts shown by dotted lines, showing the starting mechanism in an idle position. Fig. 2 shows the same in an operated position. Fig. 3 is a side elevation of Fig. 1. Fig. 4 is a vertical transverse section on the line 4—4 of Fig. 1. Fig. 5 is a vertical transverse section on the line 5—5 of Fig. 1. Fig. 6 shows 35 a portion of the operating mechanism of Fig. 5, but in an operated position. Fig. 7 is a plan view of the portion shown in section in Fig. 5. Fig. 8 is an elevation on the line 8—8 of Fig. 1, with the box cover removed. Fig. 9 is a horizontal transverse section on the line 9—9 of Fig. 8.

In detail there is shown in the drawings 40 a portion of the automobile chassis with an internal combustion engine mounted thereon. Said chassis has longitudinal members 11 and 12 and transverse members 13 and 14. The engine 10 may be of any desired construction and supported in any desired manner although here shown as mounted in 45 connection with the transverse member 14.

A hand lever 17 pivoted between its ends to the longitudinal member 12 of the chassis frame and extending vertically upward from said chassis, is pivoted to a connecting bar 18 whose other end is pivoted to a lever 60 arm 19 fulcrumed between its ends at 20 on the transverse member 13 of the chassis frame, and having a segmental gear 21 on its other end. Said segmental gear meshes with a pinion 22 pivoted at 23 on the transverse bar 13 and rigidly secured to a second pinion 24 on the same shaft. The pinion 24 has preferably a greater number of teeth than the pinion 22 and meshes with a second segmental gear 25 pivoted at 26 on the transverse member 13 and having a lever arm 27. A cable 28 or other flexible connection whose line of motion may be changed, is connected to a loop or eye 29 on a lever arm 30 of a friction band 31 and has its path of motion changed by passing over a pulley 32.

The periphery of the fly wheel 16 is substantially surrounded by the flexible metallic band 31, preferably of tempered steel, as shown in Fig. 5, with one end pivoted at 80 33 to one end of the lever arm 30 and with the other end also pivoted to said lever arm 30 but at a point more remote from the end. A return mechanism, hereafter described, is connected by a flexible connection 34 to a 85 point substantially midway of the lever 30. The end of the friction band 31 which is pivoted to the lever arm 30 has the central portion thereof cut away with the remaining portions bent to form loops 35 which 90 surround the pivot 33 on said lever, and the other end of said friction band also has its central portion cut away and the ends similarly formed into loops 36, but of such dimensions that the loops 36 may pass 95 freely between the loops 35. The loops 36 are pivoted to the lever arm 30 by means of a pin 37 extending therethrough, as shown in Fig. 5. The lever arm 30 has a projecting toe 38 extending at an angle 100 of substantially 135 degrees with the line of said lever from the end near the pivot 33. A tightening of the cable 28 will cause the lever 30 to take the position shown in Fig. 6, tightening the friction band 41 about the 105 periphery of the fly wheel and the projecting toe of said lever will press the band 31 between the loops 35 tightly against the fly wheel.

The pulley 32 is mounted on the hori- 110

zontal member 11 of the chassis frame in such a manner that it may swivel on its axis as the fly wheel is turned and the clutching mechanism moves toward the pulley.

5 A bar 40 pivoted between its ends to the frame 41 rigidly secured to the chassis frame, has one end bent to form a hook 42, its end being pressed outwardly by a coil spring 43 bearing against said supporting frame 41.

10 This hooked portion serves to stop the oscillatory motion of the friction band 31 by engaging a small projection 44 extending outwardly therefrom.

The return mechanism consists of a flat spiral spring 45 within a casing 48 and having the outer end extending through an opening 49 in said casing and connected by a flexible connection 52 to the cable 34 which is connected to the lever 30 and with the 20 inner end rigidly secured to a stud 46 pivoted upon a projection 47 in the casing and projecting through a cover 50 and secured to a handle 51. This handle has its free end bent to extend over the side of the casing 25 and it may be locked in any desired position by tightening a set screw 52 extending through the bent end against the side of the casing, as shown in Figs. 3 and 9.

To operate our invention for the purpose 30 of starting the engine the lever 17 is grasped and pulled from the full line to the dotted line position shown in Fig. 3. Such a movement will draw the connecting link 18 in a direction shown by the arrow in Fig. 1, and 35 cause the segmental gear 20 to move in an opposite direction and rotate the pinion 22. This will cause a similar rotation of the pinion 24 and an opposite oscillation of the segmental gear 25, as shown by the arrows 40 in Fig. 1, and the lever 27 will pull on the cable 28, causing the lever 30 to assume the position shown in Fig. 6, tightening the friction band 31 about the fly wheel, giving the same a partial revolution and giving the 45 pistons in the engine cylinders a corresponding movement. A release of the lever 17 will cause a slackening of the cable 28 and the lever 30 will drop back toward the position shown in Fig. 5, due to the tension of 50 the spring 45 in the casing 48. Another pull of the lever 17 will cause the lever to assume its operative position again. Thus it will be seen that the engine may be turned over, compression may be obtained in the cylinders 55 and the engine may be started without leaving the seat in the automobile.

We claim as our invention:

1. The combination with the chassis of an

automobile, and an internal combustion engine mounted thereon having a crank shaft, 60 of a wheel secured on said crank shaft, a friction band surrounding the rim of said wheel, the ends of said band being pivotally secured to a lever whereby said band may be tightened about said wheel, a cable secured 65 to the end of said lever at a point remote from said band connections, a lever arm mounted on said chassis and carrying a segmental gear said lever being operably connected to said cable, a pinion meshing with 70 said segmental gear, a second pinion secured coaxially to said pinion, a second lever arm mounted on said chassis having a segmental gear meshing with said second pinion, a lever mounted on said chassis and operably 75 connected to said second lever arm whereby a movement of said lever will tighten said band about said wheel and give said wheel and crank shaft a partial revolution, and a spring for returning said operating parts to 80 a normal position.

2. The combination with the chassis of an automobile, and an internal combustion engine mounted thereon having a crank shaft, 85 of a wheel secured on said crank shaft, a friction band surrounding the rim of said wheel, the ends of said band being pivotally secured to a lever whereby said band may be tightened about said wheel, a cable secured 90 to the end of said lever at a point remote from said band connections, a lever arm mounted on said chassis and carrying a segmental gear said lever arm being operably connected to said cable, a pinion meshing with said segmental gear, a second 95 pinion secured coaxially to said pinion, a second lever arm mounted on said chassis having a segmental gear meshing with said second pinion, a lever mounted on said chassis and operably connected to said second lever arm whereby a movement of said lever will tighten said band about said wheel and give 100 said wheel and crank shaft a partial revolution, a flat spiral spring flexibly connected to said band operating lever for returning 105 said operating parts to a normal position, and means for securing said spring under tension.

In witness whereof I have hereunto affixed my signature in the presence of the 110 witnesses herein named.

ROBERT W. LONG,
GEORGE BUTRESS
